KEY HOLDER FOR KEY CASES

Edward A. Koelling, St. Louis, Mo., assignor to
 Prince Gardner Company, St. Louis, Mo., a corporation of Missouri

Application November 6, 1950, Serial No. 194,346

4 Claims. (Cl. 70—456)

1

This invention relates to improvements in key holders for key cases. The present invention constitutes an improvement over the key holder structure disclosed in my earlier Patent No. 2,201,833, issued May 21, 1940.

An object of the present invention is to considerably simplify the construction of and reduce the number of parts in a key holder, whereby to reduce the cost of manufacture and to improve the key holder retaining and releasing function.

A further object of the present invention is to provide a guard member in association with a simplified key holder and to form the guard member with means adapted to confine it to movement in a particular direction, whereby to increase the ease with which the usual hangers for keys may be removed or placed in the holder.

The present invention consists in the combination of a holder member having a rolled marginal portion provided with one or more slots in its periphery to receive and support the headed portions of suitable key hangers, and in the provision of a guard member operably disposed within the rolled margin of the holder for obstructing the key hanger support slots. The invention also consists in the parts and elements hereinafter described, as well as equivalents thereof which may be used in a similar manner.

A more complete understanding of the present improvements may be had from the following detailed description of a preferred embodiment thereof, when considered in connection with the accompanying drawing wherein:

Fig. 1 is a front view of a key holder case in open position to show the relation of my improved key holder in a typical key case;

Fig. 2 is an enlarged fragmentary detailed view of the key holder and key hanger assembly, the parts of the assembly being turned reversed relative to the position shown in Fig. 1 whereby to reveal structural details more clearly;

Fig. 3 is a side elevational view of Fig. 2;

Fig. 4 is a view similar to that of Fig. 2 but showing the reverse side or back face of the key holder;

Fig. 5 is a detailed sectional elevational view taken at line 5—5 in Fig. 2; and

Fig. 6 is a further detailed sectional view taken at line 6—6 in Fig. 2.

Referring to the several views of the drawing, my improved key holder is disclosed in connection with a typical key case disclosed at 10,

2

wherein the key case is formed of suitable material, such as leather, and is folded to form the central panel 11 and wings or flaps 12 carrying cooperating snap elements 13. The panel 11 of key case 10 is adapted to support the holder member 14 which forms the subject of the present invention.

In Fig. 2 I have shown my improved holder member 14 reverse to the view of Fig. 1 so as not to obstruct the same by key hangers. The member 14 consists of a flat base plate 15 having one margin rolled backwardly over the plate 15 to form a cylindrical member 16 in which the free edge 17 is adapted to be brought close to or in abutment with the flat portion of the plate 15. The member 16, in cross-section, has the form substantially of that of a cylinder, the deviation from a true cylindrical shape residing in the relatively limited flat portion adjacent the edge 17. Cylindrical member 16 is provided with one or more peripherally directed slots 18 which extend from end portions 19 to enlargements 20 which are disposed in a zone adjacent the flat portion of plate 15, as is clearly seen in connection with Fig. 6. The plate 15 is provided with suitable rivet or holding elements 21 which are adapted to engage in the panel 11 of the key case 10 to secure the holder 14 in the key case, as is well understood. It is further to be noted that the free edge 17 of the plate 15 is formed with a centrally located notch 22 and with laterally spaced notches 23. These notches will be explained in more detail hereinafter.

In connection with Fig. 3 I have illustrated a typical form of key hanger 25 in which the shank portion 26 is provided with an enlarged head 27. The slot enlargements 20 are of a size adapted to receive the shank head 27 of the key holder and the remainder of the slot 18 is adapted to receive only the shank portion 26 of the key holder and provide support for the shank head 27. In this manner the key holders 25 are effectively locked into the slots 18 of the plate 15 but are permitted free rotational displacement and a desirable degree of angular displacement all within the confines of the slots 18. With key hangers of the present type, the flat portion of the cylindrical member 16 forms an inclined shelf 28 which, in the normal position of the case 10 tends to slide the hangers into the closed ends 19 of the slots 18.

In combination with the slotted cylindrical portion 16 of my holder plate, I have provided a guard member in the form of a flat plate 30 which is adapted to extend longitudinally through the

cylindrical member 16 and assume a position in obstructing relation adjacent the slot enlargements 20 so that the edge 31 of plate 30 will be effective to intercept the head portion 27 of the key holder shank 26. This action of plate 30 and edge 31 is clearly shown in dotted outline in Figs. 5 and 6. The opposite longitudinal edge portion 32 of plate 30 is adapted to be disposed in rockable relation at the inner surface of the cylindrical surface member 16 and particularly on the inclined shelf 28 adjacent the free edge of 17. Manipulation of the guard plate 30 is facilitated by the provision of a handle element 33 integrally formed and projecting from one end thereof.

The guard plate is adapted to be confined within the cylindrical member 16 and to be limited in its movement through the provision of projections or guide elements 34, there being two such guide elements 34 disclosed (Fig. 2) in connection with the present guard plate 30. With reference to Fig. 4, each of the projections 34 constitutes an enlarged portion integrally connected with the plate 30 at the portions 35 which have a somewhat reduced width in relation to the projections 34. These connecting portions 35 of projections 34 are adapted to be positioned within the notches 23 formed in the edge 17 of plate 15. In the process of forming the cylindrical member 16, the last forming operation is adapted to occur after guard plate 30 has its projections 34 and connecting elements 35 properly positioned with respect to the notches 23. In this manner, guard plate 30 is securely assembled in the key holder 14, and is permitted a certain degree of rocking motion within the cylindrical member 16 about the longitudinal edge 32 which constitutes a fulcrum edge for the guard. The limit of rocking movement of guard plate 30 is determined by bending or displacing each of the projections 34 out of the plane of the guard plate 30 (see Figs. 3 and 6), the displacement of the projections being selected so that the guard plate 30 may have its free edge 31 rocked to a position approaching the longitudinal center line or axis of cylindrical member 16. When this position is attained, projections 34 will be brought into abutment with the surface of the holder plate 15, as is shown in dotted outline in connection with Fig. 6. It will be observed in connection with Fig. 3 that the displacement of guard plate 30 to open the slot enlargements 20 for the free insertion or removal of the key hanger heads 27 will be accomplished upon clockwise displacement of the actuating handle 33.

The present key holder is rendered self-locking through the provision of a resilient element or spring 38 which is suitably riveted or otherwise secured as at 39 to the body portion of plate 15 and is directed to project into a spring guide slot 40 suitably formed in the central portion of plate 15. The spring 38 has its pressure arm 41 adapted to contact a projecting element 42, also integrally formed on the guard plate 30 at the edge 32 thereof. This construction is clearly disclosed in connection with Figs. 4 and 5. The action of the spring 38 is to maintain a force on the guard plate 30 through its projecting tab 42 so as to rock the guard plate in a direction to bring its free edge 31 into obstructing relation over or across the slot enlargements 20 in the cylindrical member 16. It will be observed, as the handle 33 of the guard plate 30 is moved in a clockwise direction, that the guard plate projection 42 will force the spring arm 41 to the right, in Fig. 5, thereby conditioning the spring to re-

turn the guard plate 30 to its normal slot obstructing position upon release of the handle 33. This action of spring 38 is further enhanced by forming projection 42 in the plane of the guard plate 30, whereas guide projections 34 are bent out of the plane thereof (Fig. 5).

A comparison of Figs. 1 and 2 should make it obvious that the key hanger elements 25, in order to be removed from or inserted in the cylindrical member 16, must be brought to a position above the cylindrical member 16. In this condition, the guard plate 30 is free to be rocked about its pivot or fulcrum edge 32 so that the final backward movement of the key hangers 25 will bring the enlarged shank heads 27 thereof into registry with the slot enlargements 20. Due consideration of Figs. 3 and 6 will make this obvious.

The present invention has been described in connection with a preferred embodiment thereof, but it should be understood that certain modifications hereof and substitutions of parts and members which are equivalents of the presently described structure may be included within the scope and spirit of the following claims.

What is claimed is:

1. A key holder for a key case comprising a base plate adapted to be secured in the key case and having a rolled marginal portion provided with a notch in the free edge thereof and a slot in the rolled portion, said slot having an enlargement at one point to receive the enlarged headed portion of a key hanger adapted to receive support at other points along said slot, a guard member disposed within said rolled marginal portion and having a fulcrum edge about which it may be moved from a normal position guarding said slot enlargement against passage of the headed portion of the key hanger, and a projection on said guard member engageable in said edge notch to retain said member within said rolled marginal portion.

2. A key holder for a key case comprising a base plate one marginal portion of which is rolled over the plate to bring the edge thereof adjacent the plate, said rolled marginal portion having a slot therein, provided with an enlargement at one point to permit passage of the headed shank of a key hanger, and said edge having spaced notches, a guard member movable in said rolled position and adapted to obstruct the slot enlargement to passage of the headed shank of the key hanger, projections on said member, each engaging in an edge notch to limit the movement of said member, and a resilient element on said base plate acting on one of said projections to bias said member into slot enlargement obstructing position.

3. A key holder for a key case comprising a plate one margin of which is rolled to provide a cylindrical body having a slot directed transversely of the cylinder axis and notches spaced along said body in the free edge of the rolled margin, said slot having an enlargement remote from the notched edge, a guard member operably disposed in said cylindrical body to obstruct the said slot enlargements, projections on said guard member extending into said notches to retain the member in said cylindrical body, and resilient means carried on said plate and acting on one of said projections to bias said guard member toward slot enlargement obstructing position.

4. In a key holder device to which key loops having enlarged heads may be removably secured comprising a plate member having a flat base part adapted to be attached to a flexible support,

a tubular part formed along one edge of said base part and having circumferential slots terminating in enlarged openings through which the key loop heads may be inserted and removed, a retainer bar positioned within said tubular part, means keying said bar to said plate member and allowing said bar to pivot in said tubular part, a spring tongue member connected to and extending from said base part engaging said bar and normally holding it in position to close off said enlarged openings, and handle means on said bar for operating same against the influence of said

spring to free said openings in removing said key loops.
